UNITED STATES PATENT OFFICE.

JAMES WOOD CARVER, OF GRANVILLE, NEW YORK.

AX.

SPECIFICATION forming part of Letters Patent No. 542,973, dated July 16, 1895.

Application filed February 10, 1894. Renewed December 19, 1894. Serial No. 532,374. (No model.)

To all whom it may concern:

Be it known that I, JAMES WOOD CARVER, a citizen of the United States, residing at Granville, in the county of Washington and State of New York, have invented certain new and useful Improvements in Axes; and I do hereby declare the following to be a full, clear, and exact description of the invention, such as will enable others skilled in the art to which it applies to make and use the same, reference being had to the accompanying drawings, and to the letters of reference marked thereon, which form a part of this specification.

My invention relates to improvements in ax-heads; and the object of the invention is to provide an improved form of head which can be more cheaply manufactured than the forms at present in common use and which can be easily withdrawn from a body of wood at any time and which will cut more readily and with less exertion.

With these and other ends in view the invention consists of an ax-head embodying novel features of construction and arrangement of parts, substantially as disclosed herein.

In the accompanying drawings, Figure 1 is a perspective view of an ax-head constructed in accordance with my invention. Fig. 2 is a plan or edge view. Fig. 3 is a central longitudinal sectional view of the same. Fig. 4 is a cross-sectional view.

Like letters of reference denote corresponding parts in the different figures of the drawings, referring to which—

35 A designates the head generally, and B the eye formed therein for the reception of a suitable handle.

The head of the ax is provided with the bit C, which terminates in a curving cutting-edge and gradually recedes to a point or apex C'. The body of the ax-head is reduced in thickness or beveled on each face from about its center or longitudinal median line toward both edges, so that in cross-section the main 45 portion of the head is substantially oval or elliptical in shape, as is shown in Fig. 4. The

side bevels D extend throughout the length of the head from the top E thereof to the outer upper edges of the bit or bevel C. This construction leaves, therefore, only a slight rib 50 F on each face of the head of the original thickness, and, as this rib is so narrow, the friction of the material into which the ax is forced is not sufficient to exert any great pull on said head.

55 While each face of the ax is provided with the side bevels D, such beveled portions are also reduced in thickness from their upper toward their lower ends, where they are only separated from the main portion of the bevel C by a slight line H.

The central longitudinal ribs F on the faces of the ax are ground off somewhat near their lower ends in order that there will be no projecting ridges to impede the downward movement of the head or to serve to prevent its easy removal from an object when desired.

By reference to Fig. 2 it will be seen that the head is practically wedge-shaped from its upper to its lower cutting-edge, and by reason 70 of this construction and the peculiar arrangement of the side bevels on each face with relation to each other and the bit C the ax can be easily driven into a wooden body and throws chips therefrom with little friction.

Having thus described my invention, what I claim as new, and desire to secure by Letters Patent, is—

The ax head herein shown and described, having the narrow flat longitudinal rib extending from the butt toward the bit of the head, having the curved cutting edge tapered and merging into the said rib and having the edges tapered from the sides of the rib the entire length of the head, for the purpose 85 stated.

In testimony whereof I affix my signature in presence of two witnesses.

JAMES WOOD CARVER.
